DESIGN FOR A TOY HAND CAR

Leslie H. Dierking, Detroit, Mich.

Application October 22, 1946, Serial No. 134,160

Term of patent 7 years

(Cl. D34—15)

To all whom it may concern:

Be it known that I, Leslie H. Dierking; a citizen of the United States, residing at Detroit, in the county of Wayne and State of Michigan, have invented a new, original, and ornamental Design for a Toy Hand Car, of which the following is a specification, reference being had to the accompanying drawing, forming a part thereof, in which:

Fig. 1 is a side elevational view of a toy hand car showing my new design;

Fig. 2 is a plan view; and

Fig. 3 is an end elevational view.

I claim:

The ornamental design for a toy hand car, substantially as shown.

LESLIE H. DIERKING.
